BOILER

Howard G. Smith, Chinchilla, Pa.

Application January 8, 1934, Serial No. 705,794

5 Claims. (Cl. 122—177)

My invention relates to a new and useful boiler and more particularly to a steel boiler which can be made in sections to be assembled at the point of use to facilitate admission through relatively small doors and windows or which can be made in one piece in relatively smaller sizes.

My invention still further relates to a boiler of this character, the structure and design of which is calculated to insure positive and rapid circulation to facilitate the production of steam and to reduce or prevent the formation of scales on the inner surfaces of the boiler.

My invention still further relates to a boiler of this character in which the water is exposed to the generated heat in relatively thin tubes to insure rapid heating of the water and in which the thin water tubes referred to are staggered above the combustion chamber thereby forcing the heated gases to pass in small volumes between the tubes to insure complete absorption of the heat of the gases by the water in the tubes thereby increasing the efficiency of the boiler.

My invention still further relates to a boiler of this character wherein a relatively large combustion chamber is provided to insure complete combustion of the fuel and the generation of maximum heat units therefrom.

My invention still further relates to a boiler of this character which comprises means for retarding the flow of the gases of combustion through the combustion and heating chambers to insure complete absorption of the heat of the gases of combustion prior to their escape into and through the flue or smoke outlet.

My invention still further relates to a boiler of this general character in which the circulation of the water in the system is aided by directing the greatest amount of heat to the front part of the boiler and by inclining the various water tubes interconnecting the front and rear water heads of said boiler from the front to the rear, thus insuring a constant flow of the colder parts of the water backwardly and downwardly from the upper drum into the rear head and conversely forcing the hotter parts of the water upwardly and forwardly through the tubes into the front water head and into the upper front portion of the liberating drum interconnecting the front and rear heads.

In the accompanying drawings:

Fig. 1 represents a front elevation of a boiler embodying my invention.

Fig. 2 represents a vertical sectional view on line 2—2 of Fig. 1.

Fig. 3 represents a horizontal section on line 3—3 of Fig. 2.

Fig. 4 represents a vertical sectional view on line 4—4 of Fig. 2.

Fig. 5 represents a horizontal sectional view on line 5—5 of Fig. 2.

Referring to the drawings in which like reference characters indicate like parts, my novel boiler comprises a front water head 1 and a rear water head 2 suitably interconnected by means of any desired number of spaced tubes 3 which are inclined downwardly and rearwardly from the front head 1 to the rear head 2. The upper portions of the front and rear heads 1 and 2 are also interconnected by the storage or liberating drum 6 which is preferably inclined from the front head 1 to the rear head 2. 8 designates a steam outlet which communicates with the liberating drum 6 above the water line thereof and 9 designates a return. Connected to the return 9 is a cold water inlet 10 which is controlled by the valve 11. The water system is provided with a drain or blowout-inlet (not shown). The boiler construction so far described is entirely covered on all sides with any suitable insulating material 12, which may be asbestos, aircell-board, or any desired insulation calculated to prevent heat dissipation. In addition to the interconnecting tubes 3 and liberating drum 6 a series of continuous tubes 13 to 16 lead from the lower portion of the rear head 2 and after zigzagging upwardly through the upper combustion chamber 14 they connect with the upper portion of the front head 1. The tubes 13 to 16 are relatively thin, are somewhat inclined upwardly from the rear head 2 to the front head 1 and are staggered with relation to each other so that each length of tube is individually and directly exposed to the upwardly surging heated products of combustion, as best seen in Figs. 1 and 4. Below the water heads 1 and 2 is constructed the fire chamber 16 which is completely enclosed, as best seen in Figs. 2 and 3, except for the opening 17 through which the nozzle of an oil burner (not shown) may be admitted, the burner proper being mounted in the outer chamber 18, access to which may be had through the hinged door 19. 20 designates a peep-hole equipped with a "Pyrex" glass panel or other transparent fire and temperature resisting material. In the walls of the outer chamber 18 are provided the grill openings 21 which serve to admit air into the outer chamber 18 and through the inlet 17 into the combustion chamber proper 16. The fire

from the oil burner (not shown) is deflected by the fire brick refractory lining 22 and the brick 23 towards the front to counteract the present tendency of the gases to escape through the smoke outlet or flue 25 without having had sufficient contact with the tubes interconnecting the heads 1 and 2 and with the heads proper. Further to insure complete contact of the flame and the gases of combustion with the water surfaces exposed in the upper chamber 14 there is provided a baffle 26 which prevents the direct entry of any of the gases of combustion directly into the flue 25 so that the flame and the gases of combustion are compelled to travel upwardly far enough to abut or impinge against the bottom of the drum 6, the gases finally flowing past the upper edge of the baffle 26 into and out through the smoke outlet 25. In operation the flame and the gases of combustion produced in the chamber 16 are deflected upwardly against the central staggered relatively thin tubes 13 to 16 as well as against the inclined tubes 3 and the exposed parts of the water heads 1 and 2, thus creating a greater heat center in the front portion of the boiler, and this together with the inclination of the tubes 3 and the tubes 13 to 16 upwardly from the rear towards the front head of the boiler results in a very rapid circulation in the direction of the arrows in Fig. 2, the rise of the hot water towards the upper portion of the front head 1 and the front of the drum 6 being accelerated by the gravitational flow of the cold water downwardly from the rear portion of the drum 6 into the rear head 2. This process is also assisted if, as in the present instance, the liberating drum 6 is also slightly inclined from the front head 1 to the rear head 2. The provision for rapid circulation, the deflection of the flame and products of combustion, as well as the exposure of the water to the heat in the manner set forth, result not only in extreme efficiency but in rapid heating of the water and in easy maintenance of the water at the degree of heat produced. It will also be noted that my novel boiler is of an extremely simple construction and that for large installations it can be shipped in sections which can be welded together at the point of use or in the event of smaller installations can be completely assembled and shipped as a unit ready for immediate connection.

I claim:

1. A boiler comprising in combination front and rear water heads, a plurality of relatively large inclined water tubes interconnecting said heads, a liberating and storage drum interconnecting the upper portions of said water heads,

and a plurality of continuous upwardly zigzagging relatively thin tubes leading from the bottom of the rear water head into the upper portion of said front water head.

2. A boiler comprising in combination front and rear water heads, a plurality of relatively large inclined water tubes interconnecting said heads, a liberating and storage drum interconnecting the upper portions of said water heads, and a plurality of continuous upwardly zigzagging relatively thin tubes leading from the bottom of the rear water head into the upper portion of said front water head, said upwardly zigzagging relatively thin tubes being disposed in a vertically staggered formation.

3. A boiler comprising in combination front and rear water heads, a plurality of relatively large inclined water tubes interconnecting said heads, a liberating and storage drum interconnecting the upper portions of said water heads, a plurality of continuous upwardly zigzagging relatively thin tubes leading from the bottom of the rear water head into the upper portion of said front water head, a completely enclosed combustion chamber below said water heads and in the rear of said boiler, and means for deflecting the flame and the gases of combustion forwardly towards the front portion of said boiler.

4. A boiler comprising in combination front and rear water heads, a plurality of relatively large inclined water tubes interconnecting said heads, a liberating and storage drum interconnecting the upper portions of said water heads, a plurality of continuous upwardly zigzagging relatively thin tubes leading from the bottom of the rear water head into the upper portion of said front water head, a completely enclosed combustion chamber below said water head and in the rear of said boiler, means for deflecting the flame and the gases of combustion forwardly towards the front portion of said boiler, a smoke outlet in the rear portion of said boiler below the top thereof, and a baffle coaxing with said smoke outlet for directing the gases of combustion upwardly against said tubes and said drum prior to their passage into said smoke outlet.

5. A boiler comprising in combination front and rear water heads, a plurality of relatively large inclined water tubes interconnecting said heads, a forwardly inclined liberating and storage drum interconnecting the upper portions of said water heads, and a plurality of continuous upwardly zigzagging relatively thin tubes leading from the bottom of the rear water head into the upper portion of said front water head.
